UNITED STATES PATENT OFFICE.

JEFFREY T. FERRES, OF LOS ANGELES, CALIFORNIA.

SLITTING AND SCORING MACHINE.

1,091,204.

Specification of Letters Patent. Patented Mar. 24, 1914.

Application filed November 7, 1912. Serial No. 729,942.

To all whom it may concern:

Be it known that I, JEFFREY T. FERRES, a citizen of the United States, residing at Los Angeles, in the county of Los Angeles and State of California, have invented certain new and useful Improvements in Slitting and Scoring Machines, of which the following is a specification.

My invention relates to machines for either slitting or scoring or both slitting and scoring paper board or corrugated paper board or the like, and the object of my invention is to produce a machine of this character having a plurality of sets of slitters or scorers or both, any one set of which is adapted to be brought into operative position leaving another set inoperative, the different sets having different adjustments for the slitting and scoring. Moreover, my construction is such that the bringing of any one set to operative position automatically brings its driving mechanism into operative position.

In the drawings Figure 1 is a side elevation of my machine; Fig. 2 an end elevation thereof; Fig. 3 a section on the line 3—3 of Fig. 1; Fig. 4 a cross-section on the line 4—4 of Fig. 1 but on a larger scale; and Fig. 5 a section on the line 5—5 of Fig. 4.

Referring to the present embodiment of my invention as illustrated in the drawings my machine is provided with a frame of suitable size and dimensions consisting of the end frames 1 adapted to rest upon the floor or support and a horizontal cross-beam 2 connected at its ends to said end frames at points intermediate their height. At the upper ends of the end frames is mounted a revolving frame comprising the opposite end members or bars 3 and two opposite cross-bars 4 connecting the ends of said end bars respectively. This revolving frame is pivoted at one end upon the bolt or stud 5 and at the other end upon the sleeve 6 which is mounted in the end members 3 and secured in proper position therein by the set screw 7. This sleeve has an eccentric bore receiving the shaft 8 which is driven in any suitable manner, as by the pulley 9.

At points on either side of the axis of rotation of the revolving frame are arranged two sets of parallel horizontal driving shafts 10, 10 and 11, 11 whose ends are journaled in the end bars 3. By preference these shafts are provided with pinions 12, 12 and 13, 13, although if desired the pinions on the outermost shafts might be dispensed with, in which event the friction of the scorers and slitters would be depended upon for rotation of such shafts. In the position 60 of the revolving frame as illustrated in the patent drawings the pinion 12 meshes with a driving pinion 14 on the inner end of the drive shaft 8 but at this time the other pinion 13 is out of mesh with the pinion 14. 65 Each of the shafts 10, 10 and 11, 11 carries one or more slitters 15 and one or more scorers 16 of any suitable or desirable construction but arranged to be adjusted longitudinally on their shafts in order to provide 70 for slitting and scoring along different lines on the paper as required in practice in the forming of different constructions of boxes. It will be understood that the paper board is passed through this machine in a horizontal plane between the two members of a 75 set of slitters and scorers. The lowermost slitters and scorers which are here represented as being secured to the shafts 10 are the ones which are in operative position. 80

Assuming that the work by the particular slitters and scorers here shown in operative position has been completed and that it is desired to work upon paper board according to a different adjustment of slitters and 85 scorers such as shown by the uppermost set in Fig. 1 in order to produce a different construction of box, the movable frame is rotated 180° with the result that the position of shafts 10 and 11 and their associated 90 devices is reversed, automatically carrying the pinion 12 out of mesh with the driving pinion 14 and bringing the other pinion 13 into mesh therewith. This automatic meshing and unmeshing of the pinions is accomplished by reason of the fact that the revolving frames revolve upon an axis (the bushing 6 and the stud 5) which is eccentric.

to the axis of the driving pinion 14. The revolving frame is held in its proper adjusted position in suitable manner as by means of the lever 17 which is mounted at 5 its inner end to the upstanding bracket 2^a on the cross-bar 2. This lever is upwardly spring-pressed by the spring 18 which normally holds the lever in locking position 10 between the lugs 19 extending upwardly from the cross-bars 4.

It will be understood that my machine may have two set positions of the slitters and scorers, thereby providing for two different constructions of box, but I prefer to 15 have the slitters and scorers adjustable longitudinally on their shafts or arbors in order to provide for a great variety of constructions of box, thereby materially increasing the range of work of the machine. 20 It is obvious that while the machine is in operation the uppermost set of slitters and scorers may be adjusted to any desired position in order to be ready for work upon a different order or construction of box immediately upon the completion of the order or 25 work theretofore passing through the machine. In this manner the time is considerably reduced inasmuch as there is no interim between the completion of one order and the 30 start upon the next order.

It is intended that my machine shall operate upon paper or board as delivered from the board making machine and hence it is necessary that the machine of this application 35 shall be placed in proper alignment therewith. In order to facilitate the work of setting the machine over in line with the other I employ the lever device shown in Fig. 1, which comprises a vertical hand 40 lever 20 pivoted intermediate its length to the brackets 21 on one of the side frames 1 and carrying at its lower end a rod 22. This rod terminates in or is provided with a pin 23 adapted to catch into a hole in the 45 floor indicated at 24. The pin 23 being a fixed point, it will be seen that a movement of the lever in one direction or the other will move the machine accordingly.

I claim:

50 1. In a machine of the class described, the combination of a rotatable frame, a plurality of devices mounted thereon for operating on the paper board one at a time, separate driving mechanisms for such devices, 55 and a common driving means in operative relationship with one of said mechanisms at a time, said frame being eccentrically mounted with respect to said means whereby one of said mechanisms will be disengaged from said means and another mechanism brought into engagement therewith.

2. In a machine of the class described, the combination of a frame, a plurality of pairs of shafts arranged therein, slitting or scor-

ing devices mounted on said shafts, said frame being rotatable to bring one pair of shafts and their devices into operative position at a time and being mounted on but eccentrically with respect to the driving means, and driving means for rotating the 70 shafts when in such position.

3. In a machine of the class described, the combination of a frame, a plurality of pairs of shafts arranged therein, slitting or scoring devices mounted on said shafts, said frame being rotatable to bring one pair of shafts and their devices into operative position at a time, driving mechanisms for the shafts, and means common to said mechanisms for operating them one at a time, said 80 mechanisms being mounted on but eccentrically of said means to cause one mechanism at a time to be brought to operating position with respect to said means.

4. In a machine of the class described, the combination of a stationary frame, a rotatable frame supported thereby on a horizontal axis, a pair of shafts on each side of such axis, slitting or scoring devices on such 85 shafts, a horizontal driving shaft, and 90 driven connections for a member of each pair of shafts, said rotatable frame being mounted eccentrically on said driving shaft whereby one driven connection is brought into operative relationship with the driving 95 shaft and the other out of operative relationship.

5. In a machine of the class described, the combination of a stationary frame, a rotatable frame supported thereby on a horizontal axis, a pair of shafts on each side of such axis, slitting or scoring devices on such shafts, a horizontal driving shaft, having a driving pinion, and a driven pinion on a member of each pair of shafts, said rotatable frame being mounted eccentrically on 100 said driving shaft whereby one driven pinion is brought into mesh with the driving pinion and the other is carried out of mesh 105 therewith.

6. In a machine of the class described, the combination of a stationary frame, a rotatable frame supported thereby on a horizontal axis, a pair of shafts on each side of such axis, slitting or scoring devices on such 115 shafts, a horizontal driving shaft, an eccentric bearing sleeve received in the rotatable frame and receiving the driving shaft, a driving pinion on such shaft and a driven pinion on a member of each pair of shafts. 120

7. In a machine of the class described, the combination of a frame, a plurality of pair of shafts arranged therein, slitting or scoring devices mounted on said shafts, said frame being rotatable to bring one pair of 125 shafts and their devices into operative position at a time, means for rotating the shafts when in such position, and a lever

normally pressed into locking engagement with the frame to hold it in different operative positions.

8. In a machine of the class described, the combination with the main frame, slitting and scoring mechanism mounted therein in fixed relationship, a lever pivoted on the

frame and a rod operated thereby to engage the floor or support for the frame.
